SURGICAL NEEDLE AND SUTURE

Owen J. Logan, Flushing, N. Y.

Application June 23, 1933, Serial No. 677,192

1 Claim. (Cl. 128—339)

This invention relates to surgical needles and sutures.

The surgical needles at present in most common use are provided with an eye for the passage of the suture. This requires a needle having a relatively large shaft where the eye is formed therein and such a needle makes a relatively large hole in the flesh which, of course, is highly undesirable. When an eyed needle is threaded, 10 the suture is doubled at least adjacent the needle and the suture passes doubled through the flesh. This also makes a relatively large hole in the flesh and the drawing of the two strands of the suture through the flesh cuts the same often at two different points.

Needles have heretofore been constructed to hold the end of a suture so that the suture will extend in a single strand from the needle. In the only construction of which applicant is informed by which this result is secured, the end of the needle opposite the point is slit and the suture is inserted in this slit in the needle after which the metal along the slit portion is swaged over the suture to hold the same in place. For 25 this reason the needle can be used with only one suture. This construction also has the disadvantage that rough edges are often formed along the slit and these injure the flesh in passing through the same.

Certain objects of the present invention are to improve the construction and mode of operation of surgical needles and sutures and to produce a construction in which the needle is attached to the end of a suture so that the suture 35 extends in a single strand from the needle and in which the needle may be attached successively to different sutures.

Other important objects of the invention are to produce a needle and suture construction in 40 which the needle may be quickly and easily attached to the end of a suture so as to leave only one strand of the suture extending from the needle and in which there will be no rough edges formed on the shaft of the needle.

With the above objects in view the invention consists in a needle and suture embodying the novel and improved features and constructions hereinafter described and particularly pointed 45 out in the claim, the advantages of which will be readily understood and appreciated by those skilled in the art.

The various features of the invention will be clearly understood from the accompanying 55 drawing illustrating the invention in its pre-

ferred forms and the following detailed description of the construction therein shown.

In the drawing,

Figure 1 is a view in side elevation illustrating a curved surgical needle and suture embodying the invention;

Figure 2 is a view of the needle illustrated in Figure 1 partly in side elevation and partly in section taken in a plane containing the axis of the needle;

Figure 3 is a view partly in side elevation and partly in section, taken in a plane containing the axis of the needle and illustrating a construction embodying the invention in modified form as applied to a straight needle;

Figure 4 is a view partly in side elevation and partly in section taken in a plane containing the axis of the needle and illustrating another modified form of the invention.

In the construction illustrated in Figures 1 75 and 2 of the drawing the invention is applied to a curved surgical needle indicated as a whole at 2. The needle comprises a body or shaft indicated at 4 to the rear end of which is detachably connected at 6 which, in the construction illustrated, is made in the form of a tube.

In order to secure the element 6 to the shaft 4 of the needle, the said element is provided with a series of screw threads indicated at 11 which are 85 arranged to engage a corresponding series of screw threads 13 formed on a reduced portion 15 of the needle shaft. The element 6 thus is secured to the shaft of the needle so that it forms an extension of said shaft. The diameter of the element 6 where it joins the shaft to the needle is preferably made substantially the same as the diameter of the rear end of the shaft so that when these parts are connected the surface of said element will be substantially flush with the 95 surface of the shaft.

The suture is indicated at 8 and is connected with the shaft of the needle by means of the holding element 6. As shown in Figure 2, the outer end of the tubular element is contracted as indicated at 10 so as to diminish to a considerable degree at this end the diameter of the passage therethrough. The suture is provided at one end with an enlargement preferably made by forming a knot in the suture as indicated at 12.

Before the tubular element 6 and the shaft 4 of the needle are assembled the suture is passed through said element from the inner or threaded end thereof and is drawn through the element until its passage is stopped by the engagement of 110

the knot 12 with the wall of the tube. The suture may then be attached to the needle by threading the element 6 onto the rear end of the shaft of the needle.

- 5 In the construction shown in Figure 3 the needle indicated as a whole at 2a is provided with a shaft indicated at 4a and a tubular element indicated at 6a is threaded on the rear end of the shaft. The outer end of said element is contracted as indicated at 10a. The suture in this figure is indicated at 8a and may be made of catgut or similar material. The suture is provided at one end with an enlargement 12a for engagement with the contracted portion of the element 6a to hold the end of the suture from being drawn through the element 6a. This enlargement is not formed by a knot in the suture as in the construction shown in Figure 2 but is produced by a swelling of the suture. This swelling may be effected 15 by dipping the suture in acid or sterilizing compound.

In the construction shown in Figure 4 the needle indicated at 2b comprises a shaft 4b and a tubular element 6b threaded on the rear end of said shaft and having its outer end contracted as indicated at 10b. The suture indicated at 8b is provided at its inner end with a sleeve 16 secured thereto. This sleeve preferably is constructed of a relatively soft metal and its outside diameter is such that it will pass into the element 6b but that it will not pass through the contracted end thereof. The sleeve is secured on a suture by swaging the same so as to contract the sleeve to grip the suture. 30 It will be noted that in the present construction the entire needle is provided with a smooth outer surface which readily passes through the flesh and that there are no rough edges which might tear or otherwise injure the flesh. The surface 35 of the shaft of the needle is flush with and blends smoothly into the outer surface of the tubular member 6 which attaches the suture to said shaft so that the entire needle may be easily drawn through the flesh.

75

After a needle has been used in sewing up a wound the suture used in the operation may be detached from the shaft of the needle merely by unscrewing the tubular member 6 from said shaft. After the sterilization of the needle a new suture holding member 6 with a suture connected thereto may be attached to the needle by threading the said member on the needle shaft. Thus the same needle may be used with a number of sutures successively. It is customary in the use of surgical needles and sutures of the present type to maintain a number of sutures with attaching elements 6 ready for use and these may be successively attached to the same needle. 80

If desired, of course, after each operation the holding element 6 may be detached from the shaft of the needle and the suture removed from said element. After the sterilization of the needle and holding element a new suture may be inserted in the said element and the element again attached to the needle. 90

It is to be understood that the invention is not limited to the particular construction and arrangement of parts of the illustrated embodiment of the invention but that the invention may be embodied in other forms within the scope of the claim. 100

Having explained the nature and object of the invention and having specifically described certain constructions embodying the invention, what is claimed is:—

In combination, a surgical needle having a point and a shaft and a shell-like suture holder, means enabling the holder to be attached to and detached from the shaft in axial alignment therewith, said holder having an axial bore and having its outer surface flush with the shaft at the point of attachment thereto, and being of equal diameter with said shaft throughout a substantial distance from its point of attachment, said holder being stream-lined towards its end remote from the shaft and having its bore so reduced adjacent said end as to serve as holding means for a suture. 110
